(57) **CLAIM**

I claim the ornamental design for a vaping device, as shown and described.

DESCRIPTION

FIG. 1 is a front-side perspective view of a vaping device showing my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an exploded front-side perspective view of an embodiment of a cartridge and a base of the vaping device. The broken lines shown represent unclaimed subject matter and form no part of the claimed design.
